FRED M. KERN, OF DETROIT, MICHIGAN, ASSIGNOR, BY MESNE ASSIGNMENTS, TO
CINCINNATI GRINDERS INCORPORATED, OF CINCINNATI, OHIO, A CORPORATION
OF OHIO

GRINDING MACHINE

Application filed November 5, 1923. Serial No. 672,773.

This invention relates to centerless grinding machines, and more particularly to a machine of this type adapted to grind to a cylindrical form various articles which are of such shapes or sizes that it is difficult for the wheels to rotate and feed the work uniformly and continuously, and detrimental markings tend to be formed thereon, and especially for grinding non-cylindrical bars 10 which are of a substantially uniform cross section.

It is an object of my invention to provide a centerless grinding machine which is adapted to reduce objects of a non-cylindrical contour to a substantially true cylindrical form in a single operation.

It is a further object of my invention to provide a two-wheeled centerless grinding machine with a work positioning member so arranged and constructed that the work will be maintained in correct axial position during grinding and rotated uniformly and fed continuously through the grinding zone.

Other objects will be apparent in the following disclosure.

In accordance with the invention, I provide a centerless grinding machine having a pair of abrasive wheels cooperating in such a manner as to rotate and grind the work and if desired to feed the work axially through the grinding zone. The wheels, preferably, are rotated in the same direction at different speeds, one of the wheels serving as a grinding wheel and rotating at a relatively high speed while the other acts as a regulating wheel and rotates at a relatively slower rate. In order to reduce an article of non-cylindrical shape, such as a rod of square cross section, to substantially true cylindrical form, I provide a rotatable work positioning member in operative association with the wheels which will permit the work to rotate continuously during the grinding operation. If the work is longer than the width of the grinding wheel, I utilize a rotatable bushing adapted to slidably engage the work and relatively guide the same while permitting it to move in the direction of its axis of rotation. The bushing is preferably so mounted that it will be rotated by the work. The

active surfaces of the wheels may be tapered, if desired, to gradually reduce a bar to cylindrical form while permitting movement thereof in an axial direction.

The invention will be more clearly understood by reference to the following description in conjunction with the accompanying drawing: in which,

Fig. 1 is an elevation of a grinding machine embodying the invention;

Fig. 2 is a section on the line 2—2 of Fig. 1 on a larger scale;

Fig. 3 is a plan view of the wheels and work support, parts being removed and the inclination of one of the wheels being exaggerated for the sake of clarity of illustration;

Fig. 4 is a section, broken away, showing a bar in operative grinding contact with the two abrasive wheels.

While the invention may be adapted for use in connection with any well known type of centerless grinding machine, for the purposes of illustration, I have shown in the drawing, a grinding machine provided with a pair of abrasive wheels mounted on axes which are in parallel planes, one of the axes being inclined to a third plane which is at right angles to the two parallel planes and passes through the other axis.

Attached to the frame 1 of this machine is a guide 2 on which a carriage 3 is slidable, being adjustable by means of the screw 4, and the carriage 3 is formed with guides for the vertical bracket 5 which may be moved up or down by means of a screw 6.

The upper end of this bracket 5 constitutes a bearing for a bushing 7 which is formed with a longitudinal hole 8 to receive a rod or bar 9, preferably of corresponding cross section, which bar is slidable in this hole and rotatable with the bushing 7. I have also found that a stationary guide with a round hole of such size that the work will turn therein without lateral movement is satisfactory. This machine is especially designed to grind bars of fibre to cylindrical form. The word "fibre" is used to designate a composite material consisting of ground wood, paper, rags or other fibrous material formed into sheets

on the usual paper making machines and impregnated with phenol condensation products such as bakelite, the finished product being also known as Celeron, Fibrok and Bakelite-Micarta. These sheets are usually cut into rods of rectangular cross section, but the material need not necessarily be formed into these sheets as it may be pressed into rods having square or any other desired cross section. These rods have usually been finished by means of ordinary cutting tools, but this material rapidly dulls even the hardest cutting tools and furthermore has a tendency to tear out and otherwise be damaged during the machining.

By the use of a grinding machine of the character shown in the drawing, rods may be introduced between the grinding wheels 10 and 11 and as these grinding wheels are formed with beveled or rounded edges 12 and 13, the pull of the inclined wheel 10 is sufficient to draw the work 9 inward and through between the two grinding wheels. The width of the cylindrical portions of these wheels must be sufficient to give enough friction on the work to move it endwise against the cutting pressure of the beveled or rounded portions. These wheels are beveled or rounded at the entrance ends to gradually reduce the work. These two wheels rotate in the same direction, the wheel 11 rotating very much faster than the inclined wheel 10 and performing the grinding, the wheel 10 serving to hold the work in proper position and to feed it along on the support 15 against which the work is held by the wheel 11 because of its higher speed and also because of its cutting action. While Fig. 4 shows the corners 12 and 13 of the two wheels in contact with the flaring surfaces of the work 9, it is not necessary that the corner 12 of the wheel 10 should so contact as a slight clearance is preferred.

When rods of this character are to be ground, a proper bushing 7 may be mounted in the bracket 5, the bushing being provided with a hole practically the cross section of the unfinished rods 9. I have found that good work can be turned out by providing a cylindrical guide hole in the upper end of the bracket 5 in which hole the work is rotatable without lateral chatter. The operator passes the front end of the rod 9 through this bushing and forces it in between the two wheels so that the end will be ground as indicated in Fig. 4, but after the front end of the rod has been ground sufficiently to approach the rear side of the grinding wheels, the action of the inclined wheel 10 becomes effective to move the rod longitudinally toward the right in Fig. 2, the rod being supported on the guide 15 and moving forward toward the right in that figure until entirely finished. The wheels are preferably almost completely enclosed in casings 16.

While I have shown a square rod being

ground to cylindrical form, the original rods may be of any other desired cross section, but it is necessary in grinding a square rod to a cylindrical shape, for example, for the grinding wheels 10 and 11 to have their corners 12 and 13 rounded to such an extent that no square shoulders will be formed on the rods, for otherwise such shoulders would prevent the rods from moving forward through the machine and thus stop its automatic action.

The axes of the two grinding wheels shown in Fig. 1 are in substantially a horizontal plane, but I do not wish to be limited thereto as such wheels may be so arranged with relation to each other that their axes may be in any other desired planes.

In the grinding of rods of fibre it is very desirable to use a solution of crude petroleum or one of its distillates, such as kerosene, either alone or in combination with other non-aqueous fluids, which has the effect of keeping the abrasive wheel from becoming clogged with the particles of fibre removed from the work and it also serves to carry away the ground particles of fibre which might have a tendency to be carried around by the grinding wheel and pass between the work and the grinding surface, thus causing scratching and tearing of the surface of the work. By using a liquid of this character a very fine high polish may be imparted to the work and the work may be ground with unusual accuracy.

The details of construction and proportions of the parts of this machine may all be varied by those skilled in the art without departing from the spirit of my invention as set forth in the following claims.

I claim:—

1. In a grinding machine, in combination, a grinding wheel adapted to be rotated at a relatively high speed, a regulating wheel adapted to be rotated at a relatively low speed, said wheels being adapted to present operative surfaces traveling in opposite directions, means between said wheels for supporting work for movement axially therebetween and to be rotated by said regulating wheel and ground by said grinding wheel, the path of travel of the work being inclined with respect to the path of travel of the operative surface of the regulating wheel whereby the regulating wheel moves the work axially as it is rotated and ground, and means for holding a work piece initially in the form of a rod of non-circular cross-section as it is fed along said work support between said wheels and is rotated and ground to a substantially circular cross-section comprising a rotatable bushing having a non-cylindrical opening shaped to the contour of said non-cylindrical rod and through which the rod passes as it enters into grinding position, the axis of said bushing being substantially aligned with the

axis of the rod portion being reduced to cylindrical shape between the wheels.

2. In a grinding machine, in combination, a grinding wheel adapted to be rotated at a relatively high speed, a regulating wheel adapted to be rotated at a relatively low speed, said wheels being adapted to present operative surfaces traveling in opposite directions, means between said wheels for supporting work for movement axially therebetween and to be rotated by said regulating wheel and ground by said grinding wheel, the path of travel of the work being inclined with respect to the path of travel of the operative surface of the regulating wheel whereby the regulating wheel moves the work axially as it is rotated and ground, and means for holding a work piece initially in the form of a rod of non-circular cross-section as it is fed along said work support between said wheels and is rotated and ground to a substantially circular cross-section comprising rotatable means exterior of said wheels adapted to hold an unground portion of the non-cylindrical rod with its axis in substantial alinement with the axis of the rod portion being reduced to cylindrical shape between said wheels, said rotatable means being rotated by said rod as the latter is rotated and fed by said regulating wheel and being arranged to permit said axial feeding movement of the rod.

3. In a grinding machine for reducing a work piece of polygonal cross-section to round cross-section, in combination, a grinding wheel adapted to be rotated at a relatively high speed, a regulating wheel adapted to be rotated at a relatively low speed, said wheels being adapted to present operative surfaces traveling in opposite directions, means between said wheels for supporting work for movement axially therebetween and to be rotated by said regulating wheel and ground by said grinding wheel, the path of travel of the work being inclined with respect to the path of travel of the operative surface of the regulating wheel whereby the regulating wheel moves the work axially as it is rotated and ground, and means for holding a work piece initially in the form of a rod of polygonal cross-section as it is fed along said work support between said wheels and is rotated and ground to a substantially circular cross-section comprising means exterior of said wheels for engaging an unground portion of the non-cylindrical rod and holding its axis in substantial alinement with the axis of the rod portion being reduced to cylindrical shape between the wheels, said means permitting said rotation and axial feeding movement of the rod.

4. In a grinding machine, in combination, a grinding throat adapted for simultaneous grinding and rotating action upon work to reduce the work to substantially cylindrical

form and comprising three means, one of which means is in the form of a grinding wheel adapted to be rotated at a relatively high speed, another of which means is in the form of a regulating wheel adapted to be rotated at a relatively low speed and in a direction to present an operative surface traveling in a direction opposite from that of the adjacent surface of said grinding wheel, and the third of which means includes a member for holding the work in operative relation to said two wheels, the operative surfaces of said three means being tapered off at the entrance end of said grinding throat thereby to reduce the work gradually as it is fed into the grinding throat.

5. In a grinding machine for reducing a work piece of polygonal cross-section to round cross-section, in combination, a grinding throat adapted for simultaneous grinding and rotating action upon work to reduce the work to substantially cylindrical form and comprising three means, one of which means is in the form of a grinding wheel adapted to be rotated at a relatively high speed, another of which means is in the form of a regulating wheel adapted to be rotated at a relatively low speed and in a direction to present an operative surface traveling in a direction opposite from that of the adjacent surface of said grinding wheel, and the third of which means includes a member for holding the work in operative relation to said two wheels, said three means being related and arranged so that said grinding throat is flared at the entrance end thereof to permit feeding thereinto and grinding down to substantially cylindrical shape a work piece of polygonal cross-section.
